APPARATUS FOR BRIGHT ANNEALING
TUBESCharles T. Paugh, Detroit, Mich., assignor to
Wolverine Tube Company, Detroit, Mich., a
corporation of Michigan

Application June 8, 1931, Serial No. 542,982

14 Claims. (Cl. 263—3)

This invention relates to an apparatus for annealing tubes and the like and more especially to an apparatus for bright annealing copper tubes.

5 The invention has as one of its objects to provide an apparatus of this nature in which tubes and the like can be annealed while being continuously carried through the apparatus.

Another object of this invention is to provide 10 an apparatus of this nature which is simple in construction and which may be produced, operated and maintained economically.

Still another object of the invention is to provide 15 a device of this character in which means is provided for conditioning the atmosphere surrounding the tubes or other work during the annealing process so as to prevent oxidization or other discoloring of the work.

The several objects, advantages and novel 20 details of construction of the invention will be made more apparent as this description proceeds, especially when considered in connection with the accompanying drawings, wherein

Figure 1 is a side elevational view of an annealing apparatus constructed in accordance 25 with this invention;

Figure 2 is a horizontal longitudinal section 30 through the furnace section of the annealing device;

Figure 3 is a transverse sectional view through 35 the furnace taken substantially on the plane indicated by line 3—3 in Figure 2;

Figure 4 is an enlarged sectional view through 40 the cooling section taken substantially on the plane indicated by line 4—4 in Figure 1;

Figure 5 is an enlarged sectional view through 45 the equalizing unit taken substantially on the plane indicated by line 5—5 of Figure 1;

Figure 6 is a fragmentary sectional elevational 50 view showing the means for conditioning the gas introduced into the conveyor tubes;

Figure 7 is a detail sectional view showing 55 the expansion joint for the conveyor tubes between the equalizing zone unit and the cooling tank unit;

Figure 8 is a transverse sectional elevational 60 view through the tube feeding mechanism;

Figure 9 is an end elevational view of the tube 65 feeding mechanism, and

Figure 10 is an enlarged detail sectional view 70 taken substantially on the plane indicated by line 10—10 in Figure 2.

Referring now particularly to the drawings 75 wherein like reference characters indicate like parts, it will be noted especially from Figure 1,

that the apparatus comprises a tube feeding mechanism or unit 10, a furnace unit 11, a heat equalizing zone unit 12, and a cooling tank unit 13.

As seen more particularly from Figures 2 and 80 3, the heating furnace unit comprises a rectangular elongated furnace chamber suitably supported by supporting members 14, the outer walls of the furnace chamber being formed of insulating material such for instance, as Sil-o-cel brick 65 15. A layer of Sil-o-cel powder 16 may be placed on top of the furnace if desired.

The interior of the furnace chamber is lined 70 with brick indicated by the reference character 17.

The upper electric heating elements 18 are suspended from the ceiling of the furnace chamber, being connected to tiles 19, the reference character 20 indicating the electric conduit for 75 supplying current thereto. This is introduced into the heating chamber through a protective casing 21.

The lower electric resistance heating elements 22 are supported on the floor of the furnace chamber, the reference character 23 indicating 80 the conduit for supplying current thereto, this conduit being introduced into the furnace through a protective casing 24.

The tubes, bars or other stock to be annealed 85 are conducted through the furnace chamber through conveyor or guide tubes 25, which are supported at spaced points throughout the length of the furnace, preferably by means of alloy steel supports 26 extending transversely of the furnace chamber and fixed in the opposite walls thereof. 90

As seen most clearly in Figure 10, the conveyor tubes 25 as they emerge from the ends of the furnace are held between the pair of clamp plates 27 and 28, the clamp plate 27 being in the form of an angle bar fixed to the furnace wall. Bolts 95 29 passing through these clamp plates act to draw the plates together to clamp the conveyor tubes 25 therebetween.

After passing out of the furnace the stock being annealed passes through the heat equalizing zone unit 12 which is shown more especially in Figure 5, comprising an elongated chamber substantially rectangular in cross section, the walls of which are insulated with Sil-o-cel brick insulation 30. Extending transversely through the 105 chamber 31 of the equalizing zone unit are supports 32 having spaced recesses or notches 33 to receive and support the conveyor tubes 25. The space between the conveyor tubes 25 within the chamber 31 is preferably filled with copper 110

chips and the like 34. This copper acts as a conductor for the heat between adjacent tubes so as to maintain a uniformity of heat throughout the series of conveyor tubes. As mentioned, the walls 5 at the top, bottom and sides of the heat equalizing zone unit are insulated. With this construction the temperature of the tubes as they leave the furnace unit is substantially maintained throughout the equalizing zone but permitted to 10 gradually decrease in the manner desirable in annealing.

In Figure 4 the cooling tank unit is illustrated in cross section. This cooling tank comprises an elongated chamber 35 substantially rectangular in cross section, water being introduced thereinto through an inlet conduit 36, the reference character 37 indicating the overflow pipe. Extending transversely of this chamber at intervals longitudinally thereof are supports 38 similar 20 to the supports 32 provided with recesses 39 for supporting the conveyor tubes 25. The body of these supports may be and preferably are, provided with apertures 40 to permit the free circulation of water through the cooling chamber 25 unit.

Inasmuch as there is considerable longitudinal expansion and contraction between the sections of the conveyor, I provide each conveyor tube with an expansion joint such as illustrated in 30 Figure 7, this expandible joint being located in each conveyor tube between the equalizing zone and cooling tank as shown in Figure 1.

In Figure 7 it will be noted that the adjacent ends of the sections of the conveyor tubes are indicated by the reference characters 25' and 25'', the section 25' having a reducer sleeve 41 threaded thereon, this reducer having a threaded engagement with a sleeve 42 upon which a cap sleeve 43 is threaded. An asbestos and graphite 40 packing 44 is located around the conveyor tube section 25'' and between the cap sleeve 43 and the end of sleeve 42. The structure permits relative longitudinal movement between the tube sections 25' and 25'' but prevents a leakage of the 45 gas within the conveyor tube. In order to insure the passage of the stock from the tube section 25' into the tube section 25'' the end of the latter is preferably flared as indicated at 45 and the edge of the tube section 25' may also be rounded 50 or bevelled as indicated at 46.

Gas is introduced into the conveyor tubes for the purpose of excluding air therefrom and also for the purpose of producing and maintaining a non-oxidizing atmospheric condition within 55 these conveyor tubes. This gas is preferably introduced into the conveyor tubes at the juncture of the furnace unit and equalizing zone unit although obviously the gas may be introduced at any desired point throughout the length of these 60 conveyor tubes.

It is frequently more convenient and economical to employ in this connection ordinary city gas but in practice it is found that city gas frequently contains a small amount of free air which will 65 result in an oxidization of the tubes.

To overcome this objection, the present invention contemplates the preheating at a high temperature of the gas and the addition thereto of a small amount of moisture which combines with 70 the free carbon released as the result of the heating, this moisture combining with the carbon to produce carbon monoxide and hydrogen, thus removing the free carbon from the mixture.

The moisture if not subsequently removed from 75 the gas is apt to slightly discolor the stock being

annealed. Therefore, in accordance with my invention this moisture together with any remaining free carbon is removed in a chamber, cooled in any desired manner as, for instance, by circulating cooling water therethrough by means of finned tube coils. This reduces the temperature of the gas to a point where the excess moisture is condensed and may subsequently be drained off. This condensate carries with it any remaining free carbon so that the gas when subsequently conducted to the tube is free from moisture at any temperature which will exist in the stock tube and is also free from carbon and free air.

The structure for accomplishing this purpose is illustrated in Figures 2 and 6 and particularly the latter figure. From Figure 2 it will be seen that the furnace is provided with a conduit or tube 47 extending longitudinally therethrough. This is the gas preheating tube. At the left hand or inlet end the tube has connected thereto a water inlet pipe 48 controlled by a needle valve 49 by means of which a controllable amount of water is introduced into the gas preheating tube. If desired, a sight opening 50 is provided so that the amount of water being introduced may be readily determined.

This water mixes with the gas and as the gas is heated to an extremely high temperature, the water vaporizes and mixes with the free carbon released upon heating the gas to combine therewith in producing carbon monoxide and hydrogen in the manner previously explained.

At the other end of the furnace, I provide a chamber 51 into which the gas from the pre-heating tube 47 is discharged and in this chamber I locate a cooling coil 52, such for instance, as a finned tube coil, through which water is circulated by means of conduits 53. This sufficiently cools the gas to condense the excess moisture which may be drawn off through a drain cock 54 located in the bottom of chamber 51. An outlet conduit 55 extends downwardly into the chamber and connects with a header 56 extending transversely of the equalizing chamber as indicated in Figure 1. This header is provided with a plurality of branch conduits 57 corresponding in number to the conveyor tubes 25 and connected to these conveyor tubes to supply the pre-conditioned gas thereto. Each conduit 57 may be 120 provided with a valve 58.

The feeding means for the tubes is best illustrated in Figures 8 and 9 and as shown comprises an upper set of rotary driving wheels 59 and a lower opposed set of driving members 60. The 130 driving members 59 are provided with peripheral wedge shaped grooves 61 and the lower driving members are provided with similar shaped grooves 62. The stock is engaged between these opposed V-shaped or wedge shaped grooves, the stock being herein indicated as a tube by the reference character T. By forming the engaging faces of the feeding members V-shaped or wedge shaped, stock of various size within given limits may be fed by the same feeding mechanism as will be 135 apparent.

The lower driving members are mounted on a shaft 63 which is rotatably journaled in bearing blocks 64 vertically slidably mounted in ways 65 formed in a supporting frame 66. The lower driving members 60 are fixed for rotation with the shaft 63 so that they will be positively driven by the rotation of this shaft. The vertical position of the bearing block 64 and consequently of the shaft 63 is limited in the downward direction 140

- by means of an adjustable stop 67. The upper driving wheels 59 are mounted upon a shaft 68 being keyed thereto by a key 69. While these driving members 59 are adapted to rotate with the shaft 68 a clearance is left between the shaft and the driving members as illustrated in Figure 8. The ends of the shaft 68 are mounted in bearing blocks 70 slidably mounted in ways 71 in the frame members 66. A spring 72 is interposed between each pair of bearing blocks at the ends of the shaft, this spring acting to maintain the lower bearing block 64 in engagement with its adjustment stop 67 and also acting to raise the other bearing block 70 and consequently the shaft 10 68. The vertical location of shaft 68 is regulated by means of an adjusting screw 73 located at each end of the frame.
- Each of the upper feeding members 59 is urged downwardly by means of a pressure roller 74 mounted on the end of an arm 75 pivoted at its end as at 76, the other end of the lever having a spring 77 connected thereto, the spring being anchored as at 78 to the frame 66. These pressure disks 74 permit a relative movement between the 20 corresponding feed member 59 and its shaft 68 equal to the amount of clearance between the shaft and the feed member. This permits each of the upper feed members to adjust itself to the accommodation of tubes or stock of varying sizes 30 or diameters, it being understood that slight variations occur in the size of the stock being fed through the device, thus making it impossible to fix each of the driving members 59 tightly around its shaft 68.
- 35 The stock after it passes between the feed members 59—60 enters the adjacent ends of the conveyor tubes 25 and then passes through the furnace, then through the equalizing zone unit and then through the cooling tank. After a 40 length of stock has passed beyond the feeding rolls it is fed onwardly through the device by the next succeeding length of stock, the ends of the stock abutting.
- The conveyor tubes hold the lengths of stock 45 in substantial alignment so that it may be fed through the device in end-to-end engagement and protects the stock while submitting it to the conditions existing in the several units of the device.
- 50 The embodiment of the invention herein illustrated has been found in practice to give excellent results but it is obvious to those skilled in the art that various changes may be resorted to in the many non-essential details of construction 55 without departing from the spirit and scope of the invention, and to this end reservation is made to make such changes as may come within the purview of the accompanying claims.
- What I claim as my invention is:
- 60 1. In an annealing apparatus of the character described, a heating chamber, a heat equalizing chamber, a cooling chamber, a stock guiding member extending through said chambers, and means for causing the stock to travel through 65 said guide member.
2. In an annealing apparatus of the class described, a heating chamber, a heat equalizing chamber connected thereto, a cooling chamber associated with said heat equalizing chamber, a 70 tubular guide member extending through said chambers, and feeding means for feeding the stock through said guide member.
- 75 3. In an annealing apparatus of the class described, a heating chamber, a heat equalizing chamber connected thereto, a cooling chamber
- associated with said heat equalizing chamber, a tubular guide member extending through said chambers, feeding means for feeding the stock through said guide member, and means producing and maintaining a non-oxidizing atmospheric condition in said guide member. 80
4. An annealing apparatus for copper tubes, bars and the like comprising, a heating chamber, a heat equalizing chamber, and a cooling chamber arranged in end-to-end relation, a guide tube extending through said chambers, and stock feeding mechanism located adjacent one end of said heating chamber for feeding the stock to be annealed through said guide tube. 85
5. An annealing apparatus for copper tubes, bars and the like comprising, a heating chamber, a heat equalizing chamber, and a cooling chamber arranged in end-to-end relation, a guide tube extending through said chambers, stock feeding mechanism located adjacent one end of said heating chamber for feeding the stock to be annealed through said guide tube, and means for producing and maintaining a non-oxidizing atmospheric condition in said guide tube. 90
6. An annealing apparatus for copper tubes, bars and the like comprising, a heating furnace, electric heating elements arranged in said furnace, a heat equalizing chamber, a cooling chamber, means for circulating a cooling medium through said cooling chamber, a tubular guide member extending substantially continuously through said chambers, and means for feeding the stock to be annealed through said guide member. 100
7. An annealing apparatus of the character described comprising, an elongated heating chamber, electric means for heating said chamber, an elongated heat equalizing chamber having one of its ends connected to one end of said furnace, a cooling chamber, means for circulating a cooling medium through said cooling chamber, a stock guiding tubular member extending through said heating chamber, equalizing chamber and cooling chamber and open at its opposite ends, means for maintaining a non-oxidizing atmospheric condition within said tubular member, and means adjacent the furnace for feeding stock to be annealed into and through said tubular member. 110
8. In an annealing apparatus of the character described, an electric heating furnace, a heat equalizing chamber arranged in end-to-end relation to said furnace, stock guiding tubes extending through said furnace and equalizing chamber, means in said equalizing chamber for insulating said tubes to effect a slow cooling of the stock which passes therethrough from the furnace, a cooling chamber, means for cooling said chamber, and means extending through said cooling chamber for receiving and guiding the stock while preventing direct contact therewith of the cooling medium. 120
9. In an annealing apparatus of the character described, a heating chamber, a heat equalizing chamber, and a cooling chamber, said chambers being arranged in end-to-end relation, a plurality of tubular guide members through which the stock is fed, said guide members extending through said chambers to subject the stock to the conditions existing therein while maintaining the stock completely enclosed, and feeding means arranged at one end of the furnace for introducing the stock into and feeding the same through said guide tubes. 130
10. In an annealing apparatus of the character

described, a heating chamber, a heat equalizing chamber and a cooling chamber, stock guiding tubes extending successively through said chambers, means for introducing the stock to be annealed into and feeding the same through said guide tubes, said heat equalizing chamber including means for insulating said tubes from the atmosphere and means for establishing a heat conducting connection between adjacent tubes, 10 for the purpose set forth.

11. In an annealing apparatus of the character described, a heating chamber, a second chamber, a tubular guiding member extending through said heating chamber and said second chamber, and 15 means possessing a high degree of thermal conductivity surrounding said guiding member within said second chamber.

12. In an annealing apparatus of the character described, a heat equalizing chamber, a plurality of tubular guide members extending through said chambers, and means in said heat equalizing chamber establishing a heat conduct-

ing connection between adjacent tubular members.

13. In an annealing apparatus of the character described, a tubular guide member, and means for supplying a non-oxidizing gas to said tubular guide member, said means including a source of illuminating gas, means for moistening said gas, means for heating said moistened gas, and means for cooling said moistened gas to precipitate the excess moisture therefrom. 80

14. In an annealing apparatus of the character described, a heating chamber, a heat equalizing chamber and a cooling chamber, stock guiding members extending successively through said chambers, means for introducing the stock to be annealed to and feeding the same along said guiding members, said heat equalizing chamber including means for insulating the stock from the atmosphere, and means for establishing a heat conducting connection between adjacent strips of stock. 90
